UNITED STATES PATENT OFFICE.

JOHN D. AVERELL, OF NEW YORK, ASSIGNOR TO WILLIAM CURRY, OF BROOKLYN, N. Y.

MERCURY GAS-GOVERNOR.

SPECIFICATION forming part of Letters Patent No. 296,664, dated April 8, 1884.

Application filed February 2, 1884. (No model.)

To all whom it may concern:

Be it known that I, JOHN D. AVERELL, a citizen of the United States, residing in the city, county, and State of New York, have invented a new and useful Improvement in Mercury Gas-Governors, of which the following is a specification.

This invention relates to an improvement in the construction of the class of gas-governors in which the regulating-valve is suspended from the center of an inner and outer inverted cup floating in mercury, and both the regulated and unregulated pressure of the gas acting on the valve as the regulating medium of the governor, and in which the governor has a cap over its case, which cap is provided to be locked to the case.

The object of the invention is, first, to provide the regulating-valve against jarring or trembling during its close cutting off the gas supply to the governor. Said object is, secondly, to provide against overflowing the mercury seals, to stop any flow of mercury into the valve-chamber upon the valve and into the meter, and thereby causing the destruction of soldered joints of brass-work and parts coming in contact with mercury. Said object is, thirdly, to have, in connection with the regulating-valve, a catch or stop within the locked case of the governor, for the purpose of stopping the valve entirely off its seat for the alternate test of the loss of gas by allowing the gas to pass through the governor without regulating its pressure.

The first part of the improvement consists in the arrangement and construction of the regulating-valve and its floating cups with a ballast or balance-weight, so as to have their center of gravity considerably below their line of buoyancy, and by this means render the motion of the valve from and to its seat stable and steady, and obviating the jarring and trembling of the valve during close cutting off the supply. The second part consists in constructing the inner or covered sides by the inner cup of the mercury-chambers higher than the outer; and the exterior side with an overflow-aperture, so that in filling the mercury seals, which are connected, the mercury cannot be raised above said overflow, and cannot

overflow into the valve-chamber in pouring it properly. The third part consists in providing the top guide-plate with a pivoted catch or stop, which can be turned upon the guide-opening, and thereby hold the top end of the valve-rod down, and thereby the valve entirely below the valve-seat, and allowing the gas to pass entirely unregulated, for the purpose before stated.

The drawings annexed represent, in Figure 1, a central longitudinal vertical section of the governor with my improvements. Fig. 2 is a detached top view of a portion of the top guide-plate with my improved valve-rod stop. Fig. 3 is a detached face view of the opening in the partition between the two mercury-chambers of the governor.

A represents the governor-case, which has the gas-inlet B attached to the gas-meter, and has the gas-outlet C, to which the house-pipe is connected. In the lower portion of the case are arranged the inlet or valve chamber D and the discharge or outlet chamber E. In the horizontal part F of the partition between said chambers is made the valve opening and seat G. The regulating-valve H is arranged under the seat G, and is attached to the vertical valve-rod I, the bottom end of which is guided in the bottom guide-plate, J, and the top end of the same is guided in the top guide-plate, K. In the portion of the case between the top guide-plate and the chamber D and E are arranged the mercury-chambers L and M and the inverted cups N and O. Said cups are made with a crown, to render them very stiff. They are both attached to the valve-rod I centrally below the top guide-plate.

P represents the cover of the governor, which is hinged at R to the case A, and has a loop joining a secondary loop on the opposite side of the case. In these loops a pad or other lock is applied for locking the cover to the case.

The cups N and O are made circular, and concentrically attached to the rod I, upon which, below the valve, is attached the ballast or balance-weight Q. Said weight may be cast or formed on the valve, or it may be separately attached to the rod by a screw-nut, S, as shown; but its weight and dimension are properly proportioned to the area of the valve and those

of the cups and to the pressure of gas, so as to effect the desired stable and steady motion of the regulating-valve.

Both the inner mercury-chamber, L, and 5 outer chamber, M, are circular, and concentrically arranged. The outer side of the chamber M or the case A has two apertures, T and U, which are plugged by small screw-plugs T', and the aperture T is arranged at the bottom 10 of the chamber M, and the aperture U at the proper level of the mercury. The inner side, L', of the chamber L is constructed to rise above the aperture U. A large notch or passage, V, is made in the partition between 15 the said chambers, so that both freely communicate the mercury. After the governor is attached to the meter and ready to receive the mercury, the plug T' is withdrawn from the aperture U and the mercury is poured in, 20 filling both chambers until the level of said aperture U is reached. The flow is then stopped and the aperture is again plugged. The gas may now be turned on by the opening W around the valve-rod. The gas passes 25 under the inner cup, N, and also through the valve-seat G into the discharge-chamber E, and into the room or building pipe by the outlet C. By means of the opening X in the partition between the chambers L and M, the gas 30 passes under the cup O.

Upon the top guide-plate, K, is employed the pivoted catch or stop Z. It is secured by

the screw or rivet Y, and is made so that it can be turned with its loose end over the guide-opening, holding the cups and valve down so 35 as to allow a free passage of the gas through the governor, allowing the gas to pass unregulated.

What I claim as my invention, and desire to secure by Letters Patent, is— 40

1. The combination, in a pressure-regulator, of the valve H, its guide-rod I, the cups N and O, with removable ballast or weight Q, arranged on the rod below the valve, whereby its center of gravity is lowered, and the apparatus is thereby rendered more steady, substantially as set forth. 45

2. The combination, in a pressure-regulator, of the spider guide-plate K, having the stop Z, the lower guide-nut, J, the weighted valve-rod I, with the interposing valve and cups, whereby the mercury-cups and valve are more securely held in a vertical central position when lowered, substantially as described. 50

3. The combination of the top guide-plate, K, with the stop Z and its pivot Y, arranged to stop the rod I, substantially as and for the purpose herein stated. 55

In testimony whereof I hereunto set my hand.

JOHN D. AVERELL.
